UNITED STATES PATENT OFFICE

BENJAMIN W. JONES, OF SCHENECTADY, NEW YORK, ASSIGNOR TO GENERAL ELECTRIC COMPANY, A CORPORATION OF NEW YORK

ANTIFREEZING TIP FOR STARTERS

Application filed June 6, 1930. Serial No. 459,514.

My invention relates to switches of the bridging contact type and has for its object the provision of a device of this character in which the contacts will not stick or "freeze" together under the heaviest service.

In the operation of electromagnetic switches, especially as used in the control of electric motors where the switches are operated very frequently and the currents are heavy, it occasionally happens that the arc formed between the contacts fuses the metal and causes the contacts to stick together due to the formation of a slight weld between them. This most frequently happens where the magnetizing winding is only instantaneously energized so as to cause the contacts to touch each other without being actually forced into firm engagement. It also sometimes happens because of the small opening of the contacts due to very slow decrease of magnetic pull and other causes. In the type of contact for electromagnetic switches now well known in which the contacts slide or roll upon each other so as to produce a wiping action, any slight welding or sticking will be overcome by the wiping action if the contact is once "wiped home".

In certain types of starters employing the electromagnetic switch, particularly in small starters where it is desirable to obtain a double break for the arc so as to obtain a good interruption with a small and simple construction, two stationary fingers per phase are employed which are bridged by a moving finger. This bridging motion has the desired double break but is subject to the objection of "freezing" due to the fact that sliding or rolling of the contacts is difficult to obtain during the operation of the contacts, and would not be particularly desirable since it causes excessive wear.

It is, therefore, the principal object of my invention to provide a movable member of the character above described in which freezing of the contacts will not take place.

In the preferred embodiment of my invention, I provide the moving finger which carries the bridging contacts with a projection at one side thereof. This projection cooperates with a second projection which causes a

tilting or rocking of the finger carrying the bridging contacts after the stationary contacts are engaged thereby. This tilting immediately after the circuit is made is easy because the metal which may have melted is still soft and easy to break and "freezing" is eliminated.

In the drawings, Fig. 1 shows my invention in perspective; Figs. 2 and 3 represent different positions of the contacts; Fig. 4 is a view of the finger carrying the bridging contacts and Fig. 5 is a cross section of Fig. 4.

Referring to Figs. 1, 4 and 5, it will be seen that mounted upon a base 10 are the stationary contacts 11 and 12. A movable member 13 has attached thereto the arm 14 which supports the moving bridging member or finger 15 carrying the bridging contacts. Fastened to the arm 14 by means of the screw 17 is the stub or supporting member 16 upon which the moving finger 15 is slidably mounted. The spring 18 biases the moving finger 15 to the end of the stub member and against the portion 19 thereof away from the arm 14. The finger 15 is provided with the U-shaped projection 21 at one side thereof. This projection cooperates with the projection 22 formed on the arm 14. The action of the contacts during engagement is described below.

Fig. 2 represents the stationary contact and the movable contact before engagement of the bridging member with the stationary contacts. As the contacts on the movable finger 15 move into engagement with the stationary contacts 11 and 12, the flat surfaces of the contacts engage with each other. It is at this moment that the large rush of current passes through the contacts and if there is any tendency for the metal to melt, this action will take place at this time. As the arm 14 continues to move further in, forcing the contacts into closer engagement, the projection 21 engages the projection 22 and tilts the finger 15, as shown in Fig. 3, placing the spring 18 under compression. This tilting action breaks any slight weld that may have taken place when the contacts were temporarily placed in a slightly plastic state. When the switch is opened the contacts easily pass out of engagement with each other. It

will thus be seen that I have provided a positive means for preventing freezing of the contacts during operation of the switch.

The embodiment of the invention illustrated and described herein has been selected for the purpose of clearly setting forth the principles involved. It will be apparent, however, that the invention is susceptible of being modified to meet different conditions encountered in its use and I, therefore, aim to cover by the appended claims all modifications within the true spirit of my invention.

What I claim as new and desire to secure by Letters Patent of the United States, is:—

1. A switching mechanism comprising stationary contacts, a bridging member cooperating with said contacts comprising a resiliently mounted bridging element carrying contacts, a projection on said element and means cooperating with said projection for tilting said last contacts laterally with respect to said stationary contacts after engagement with said stationary contacts to prevent "freezing".

2. A switching mechanism comprising stationary contacts, a bridging member provided with contacts for cooperating therewith, a projection on said bridging member, means cooperating with said projection on said bridging member for causing a lateral rocking of said contacts carried thereby after contact with said stationary contacts to prevent "freezing".

3. A switching mechanism comprising a pair of stationary contacts, a movable member carrying a resiliently mounted element provided with contacts for cooperating therewith to bridge said stationary contacts, a projection on said element, means cooperating with said projection to tilt said element and contacts laterally after engagement with said stationary contacts.

4. A switching mechanism comprising stationary contacts, a movable member provided with a stub thereon, a finger slidably mounted thereon and carrying contacts for cooperating with said stationary contacts and provided with a projection at one side thereof, a projection on said movable member cooperating with said first projection to tilt said finger on said stub when said contacts are in engagement and a biasing means for holding said finger in an untilted position when said contacts are out of engagement.

5. A switching mechanism comprising a pair of stationary contacts, a movable member provided with a stub, a finger provided with contacts for bridging said stationary contacts and slidably mounted on said stub, a spring on said stub for biasing said finger to one end of said stub, a projection on said finger at one side thereof, a second projection on said movable member cooperating therewith for tilting said finger on said stub

after engagement of said movable and stationary contacts.

6. In a switching mechanism, stationary contacts, a movable contact carrying member cooperating therewith and comprising an arm, a stub thereon, a contact carrying finger slidably mounted on said stub and biased toward the end of said stub away from said arm, a projection on said finger at one side thereof and a projection on said arm cooperating therewith for causing tilting of said finger on said stub when said contact carrying member moves into engagement with said stationary contacts.

In witness whereof, I have hereto set my hand this 5th day of June, 1930.

BENJAMIN W. JONES.
